UNITED STATES PATENT OFFICE.

SYLVESTER L. GOOKIN, OF QUINCY, MASSACHUSETTS, ASSIGNOR TO UNITED SHOE MACHINERY CORPORATION, OF PATERSON, NEW JERSEY, A CORPORATION OF NEW JERSEY.

FASTENER-INSERTING MACHINE.

Application filed September 12, 1927, Serial No. 219,108, and in Great Britain March 4, 1927.

This invention relates to fastener-inserting machines and is herein illustrated as embodied in a machine for inserting, for example, eyelets having non-circular barrels.

5 In eyeleting machines designed to insert eyelets successively at high speed the eyelets are supplied to the inserting tools by a raceway, one of the inserting tools having a spindle arranged to enter the barrel of an eyelet in the delivery end of the raceway to pick the eyelet therefrom. When non-circular eyelets are inserted in a shoe upper it is required that they shall all be positioned in the same relation to the adjacent edges 10 of the shoe upper. Thus, when each eyelet, as in the example herewith illustrated, is formed with a barrel having one or more flat sides the eyelets should all be inserted so that one flat side of each will be parallel 15 to the adjacent edge of the upper over which the lacing is to extend, but it is to be understood that the invention hereinafter described is not limited to the type of eyelet shown.

20 In eyelet-inserting machines provided with automatic work-feeding mechanism and with a raceway for presenting the eyelets to one of the setting tools the raceway usually extends substantially at right angles to the 25 direction of work-feeding movement. Consequently, when such a machine is used to insert eyelets having so-called oval barrels, as shown, the raceway maintains the major diameter of the barrel of each eyelet substantially at right angles to the direction of work-feeding movement, and it therefore becomes 30 necessary to turn each eyelet substantially ninety degrees about its axis before it is inserted into the work so that its flat sides and 35 the major diameter of the barrel will lie 40 parallel to the lacing edge of the upper.

In eyelet-inserting machines heretofore fitted to deal with this problem of turning non-circular eyelets the turning movement 45 has occurred after disengaging each eyelet from the raceway. In one former type of machine the problem has been solved by turning the tool that takes the eyelets from the raceway, but this requires additional mechanism to furnish the turning movement. In 50 another former type of machine the tool that takes the eyelets has no turning movement but its spindle is so shaped that the eyelet, in sliding down thereon, is turned relatively

thereto. The turning effect thus produced is 55 dependent upon gravitation of the eyelet and is therefore uncertain, particularly when operating at high speed, since the eyelet sometimes sticks and at other times is not fully turned when forced against the work.

60 In view of the conditions above described an object of this invention is to provide improved means for turning non-circular fasteners to a predetermined position, and in accordance with this object the desired turning 65 is effected by the conjoint actions of a fastener-inserting tool and a raceway while the fastener is in contact with, and under control of, the raceway.

Another feature of the invention consists 70 in a fastener-inserting tool having an improved type of spindle for picking from a raceway fasteners having barrels of elongated cross-section and for furnishing a force to turn the fasteners while the latter 75 are engaged with the raceway. As shown, the entering end of the spindle is tapered in such a way as to offset the tip thereof from the median longitudinal line of the body portion, so that the tip, on entering a barrel of the 80 cross-section mentioned, will occupy the most advantageous position as a pivot about which the fastener may turn.

According to still another feature of the invention, the raceway is arranged to present a fastener to the aforesaid spindle with the fastener rotatively out of register with the cross-sectional shape of the body portion 85 of the spindle, and the spindle and the raceway are relatively moved, first, to insert the 90 tapered end of the spindle into the fastener located at the delivery end of the raceway, and then to turn the impaled fastener positively to a position in which the cross-sectional shapes of the fastener barrel and the 95 body of the spindle are in register with each other. This relative movement comprises a component lengthwise of the spindle to insert the latter into the barrel of the fastener and a component transverse to the spindle to 100 turn the fastener into register with the cross-section of the body of the spindle before the fastener is disengaged from the raceway. Thus, the control over the fastener, as well as the fastener itself, is transferred from the 105 raceway to the spindle before the raceway relinquishes its control over the fastener, and since the body of the spindle is shaped to

maintain the position of the fastener established by the cooperative action of the raceway and the spindle it is assured that successive fasteners will all be uniformly positioned.

5 In the drawings,

Fig. 1 is a perspective view of a portion of an eyelet-inserting machine which embodies the novel features of the present invention hereinafter described;

10 Fig. 2 illustrates a portion of a shoe upper representing a specimen of work performed by said machine;

15 Figs. 3, 4 and 5 are top plan views representing successive stages of operation of the delivery end of the raceway and the lower eyelet-inserting tool to which the eyelets are delivered by the raceway;

20 Fig. 6 is a perspective view of the parts included in Figs. 3, 4 and 5, the direction of the view being substantially the same as that of Fig. 1, and

25 Fig. 7 is a vertical section including a portion of the lower fastener-inserting tool and a portion of the delivery end of the raceway in a relation corresponding to that of Fig. 4.

30 The general organization of the illustrated machine is substantially the same as that more fully shown and described in United States Letters Patent 1,228,768 granted June 5, 1917, on application of P. R. Glass with the exception of certain differences herein specified.

35 The frame 10 of the machine is provided with bearings for a horizontal operating shaft 12, one of which bearings is indicated at 14. The front part of the frame 10 is provided with stationary bearings 16 for a vertical plunger 18 which carries at its upper end 40 an eyelet-inserting tool 20. This tool is specially designed to insert eyelets having non-circular barrels but the plunger 18 is arranged and operated as described in said Letters Patent. A split sleeve 22 is tightly clamped to the plunger and is provided with a block 24 which is pivotally connected thereto. The block 24 is straddled and engaged by an operating lever 26 having a forked construction at its forward end. The rear end of the lever 26 is formed and arranged to be actuated by a crank (not shown) on the operating shaft 12, the construction being the same as that shown in said Letters Patent to produce relatively slow motion of the plunger 18 through 45 the initial stages of its upward stroke, relatively rapid motion during the final stages of the upward stroke, relatively rapid motion during the initial stages of the downward stroke, and relatively slow motion during the 50 final stages of the downward stroke. During the relatively slow motion in the initial stages of the upward stroke of the plunger the tool 20 picks an eyelet from the raceway, as hereinafter described.

55 The raceway 28, although not shown in its

entirety, is arranged to turn about a vertical axis indicated by broken line 30 in Fig. 1, a stem formed on the framework of the raceway being journaled in a boss 32 formed on the main frame 10. The raceway is inclined and is provided at its upper end with a hopper (not shown) and with well-known mechanism for feeding eyelets flange down from the hopper into the raceway. The eyelets are delivered in this position to the tool 20.

70 The mechanism for oscillating the raceway about the vertical axis 30 differs from that disclosed in said Letters Patent and will therefore be described herein, the essential difference being in the timing of its motions, the better to coordinate said motions with those of the plunger 18, so that the problem of transferring the eyelets from the raceway to the inserting tool 20 and of turning the eyelets about their axes incidentally to such transfer shall be solved as satisfactorily as possible. Instead of utilizing a crank, as shown in said Letters Patent, to operate the raceway, the operating shaft 12 is provided with two cooperative cams 34 and 36 which act, respectively, on two laterally offset arms 38 and 40 of a forked lever suspended from a horizontal pivot 42. The cams 34 and 36 are coordinated to maintain contact continuously with the arms 38 and 40. A link 44 is connected to the lower end of the arm 38 by a universal joint 46 of the ball-and-socket type. The forward end of the link 44 is connected to an arm 48 of a bell-crank lever by a universal joint of the articulated type, the construction comprising an intermediate block 50, a pivot 52 connecting said block and said link, and a pivot 54 connecting said block and said arm 48. The bell-crank lever is arranged to be oscillated about a vertical axis, its ends being mounted on trunnions one of which is indicated at 56. An arm 58 formed on the bell-crank lever is connected to the framework of the raceway by two pivots 60 and 62 and a connecting link 64.

75 100 105 110 115 120 125 130 The machine also comprises a stationary horizontal work table 66, a punch clock 68 embedded therein, a combined punch and clenching tool 70 the pilot or punching portion 72 of which cooperates first with the punch block in the usual manner to punch an eyelet-receiving hole in the work, and thereafter feeds the work from right to left to locate the punched hole in register with the inserting tool 20, and finally enters the barrel of the ingoing eyelet to guide the barrel to the clenching surface of the tool 70.

80 85 90 95 100 105 110 115 120 125 130 The punching and clenching tool 70 is affixed to a vertically movable plunger 74 arranged to slide in bearings 76 formed in a horizontally movable feed carriage 78. Vertical reciprocation is imparted to the plunger 74 by mechanism like that more fully shown and described in said Letters Patent. So far as said mechanism is illustrated in Fig. 130

1 it comprises toggle members 80 of which there are two pairs, and links connecting them with an operating bar, one of said links being indicated at 82.

5 The feed carriage 78 is arranged to slide on a stationary, horizontal rod 84 and is provided with a rod 86 arranged to slide in bearings 88 formed on the main frame 10. The mechanism for reciprocating the feed carriage, so far as it is shown in Fig. 1, comprises a lever 90, the construction of this mechanism being the same as that of the corresponding mechanism shown in said Letters Patent. The machine is also provided with a presser 10 foot 92, mechanism for operating it, and an edge gage 94, to all intents and purposes the same as the corresponding elements more fully disclosed in said Letters Patent.

Referring to Fig. 7, the plunger 18 is tubular and the eyelet-inserting tool 20 is arranged in the bore of said plunger and secured therein by a screw-threaded nipple 96. To prevent the tool 20 from turning relatively to the plunger 18 the former is provided 25 with a key 98 and the latter with a vertical notch 100 to receive said key. A spline (not shown) prevents turning movement of the plunger 18. A sleeve 102 is arranged in the bore of the plunger 18 to support the tool 20 30 and is vertically adjustable relatively to the plunger to regulate the pressure with which the tool 20 cooperates with the tool 70 to clench the eyelets. Adjustment of the sleeve 102 for this purpose is effected by a screw 35 104 arranged to abut the lower end of the sleeve, the lower portion of the plunger being provided with an internal screw-thread to cooperate with the adjusting screw.

The tool 20 is provided with a spring-40 pressed spindle the body portion of which, indicated at 106, is of non-circular cross-section conforming to that of the barrels of the eyelets to be inserted. The two flat faces of the body portion 106 are maintained parallel 45 to the lines of work-feeding movement by a corresponding formation of the hole in the tool 20. This spindle has a tapered portion 108 at its upper end to facilitate its entrance into the eyelets and to facilitate the turning 50 of the eyelets as hereinafter explained. The lower end of the spindle 106 is provided with a head 110 which is normally maintained against the lower end of the member 20 by a compression spring 112 arranged in the sleeve 55 102. This spring permits the spindle to yield relatively to the member 20 in the event that the normal operation is prevented through any cause such, for example, as a deformed eyelet in the raceway or an obstruction in 60 the barrel of the eyelet.

Fig. 2 shows a portion 114 of a shoe upper in which a series of non-circular eyelets have been inserted to illustrate a specimen of work to be performed. The edge 116 of the upper 65 per is one of the two edges across which the

shoe lacing is to extend. The type of eyelet shown by the drawings is but one of various types having non-circular barrels. As shown in Fig. 2, the eyelets have flanges 118 and flat-sided oval barrels 120. When eyeleting 70 shoe uppers with eyelets the barrels of which have one or more flat sides, as in the illustrated example, it is usually preferred to insert such eyelets so that a flat side of each barrel will be parallel to the edge 116 to provide a straight bearing for a flat shoe lace. This condition creates a problem in automatic eyelet-inserting machines, since the eyelets are supplied in such machines by raceways arranged to extend substantially at 75 right angles to the direction in which the work is fed. It thus follows that when, as in the illustrated machine, the raceway is used to conduct eyelets having oval barrels, the major diameters of the barrels will be parallel to the raceway and therefore approximately at right angles to the edge 116 of the upper, which edge necessarily extends parallel to the direction of feed and lies in contact with the edge gage 94. The above-mentioned problem 80 consists in turning the eyelets about their axes from the position they occupy in the raceway to the position they should occupy when inserted into the work as above explained. 85

Accordingly, the present invention provides means for turning the eyelets to the required position in the manner about to be described. An outlet passage 122 (Fig. 3) is formed at the left-hand side of the delivery 100 end of the raceway, and the barrels 120 of the eyelets pass through this passage incidentally to the removal of the eyelets from the raceway. As the leading eyelet reaches the delivery end it is partially turned by a deflecting surface 124 formed on the right-hand guiding strip of the raceway. The eyelet, on being deflected and partially turned by the surface 124, is arrested by a detent 126 so that the said eyelet occupies the position 105 shown in Fig. 3 at the moment when the upper end 108 of the spindle is inserted into it. Even when the eyelet stands in this position it is still rotatively out of register with the body portion of the spindle. A detent 110 115 126 is carried by the raceway and is maintained in the position shown in Fig. 3 by a compression spring 130. In this position the left-hand end of the detent 126 obstructs the passage 122 so that the barrel of the eyelet 120 cannot pass therethrough without displacing the detent against the pressure of the spring 130.

The mechanism herein described for oscillating the raceway about the axis 30 and that 125 for operating the plunger 18 are coordinated not only to transfer the leading eyelet from the raceway to the inserting tool 20 but also to turn the eyelet positively to the desired position while it is in contact with and 130

under control of the raceway. The motions effected by these two mechanisms are such that the delivery end of the raceway stands initially in the position shown in Fig. 3, in which position the eyelet at the delivery end is only partially in register with the tapered portion 108 at the upper end of the spindle body 106. This partial register is sufficient, nevertheless, to enable the tip of the spindle 10 to enter the barrel of the eyelet as the plunger 18 rises. At this stage the upward movement of the plunger 18 is relatively slow, but irrespective of the rate at which it rises, the spring 112 under the spindle 106 (Fig. 7) will 15 permit the spindle to yield relatively to the member 20 if occasion requires. When the tip of the spindle has been inserted into the eyelet, as above explained, the raceway-operating mechanism effects relatively rapid 20 movement of the delivery end of the raceway toward the right, as indicated by an arrow in Fig. 3, thus removing the raceway from the path of the tool 20. As the raceway describes the motion last specified, the 25 end surface 132 of the left-hand guiding strip of the raceway engages a flat side of the barrel of the eyelet now occupied and impaled by the tip only of the spindle. The tip of the spindle functions at this stage as 30 a pivot about which the eyelet is turned to the position shown in Fig. 4 by a wiping action of the surface 132 on the flat of the barrel as the latter is drawn through the outlet passage 122 between the surface 132 and the 35 yielding detent 126. The eyelet is thus turned by the surface 132 into register with the body 106 of the spindle so that the latter, being now relieved from all restraint, may be projected through the eyelet by the spring 112 40 as shown in Fig. 7, in which the detent 126 and the left-hand guiding strip of the raceway not only overlap the flange 118 of the impaled eyelet but also clamp the barrel 120 thereof. Thus the spindle 106 is inserted far 45 enough into the eyelet to prevent any subsequent turning movement before the eyelet is disengaged from the clamping elements 126 and 132. It is therefore assured that the eyelet, having been turned by the raceway to the desired position, will be maintained positively in that position by the spindle 106, although the eyelet may thereafter drop until its flange is seated upon the member 20.

55 Fig. 5 shows the raceway as having completed its motion to the right and shows the impaled eyelet on the spindle 106 as having been wholly disengaged and removed from the raceway. This figure also shows the next 60 succeeding eyelet in the raceway as having progressed to the delivery end, as having been deflected and partially turned by the deflecting surface 124 and as having been arrested by the detent 126 which now obstructs 65 the outlet passageway 122.

During the aforesaid operations of the raceway and the eyelet-inserting tool 20, the combined punching and clenching tool 70 is operated, first, to punch a hole in the work to receive the eyelet, and secondly, to feed the work and thereby place the punched hole in register with the tool 20. The tool 70 is thus placed in register with the tool 20 before the latter has risen far enough to insert the eyelet, but the tool 20 continues to rise while 75 the tool 70 remains stationary, thereby inserting the eyelet and clenching it in well-known manner. Thereafter the tool 70 rises and moves to the right preparatory to punching another hole in the work, the tool 20 descends below the raceway, and the raceway returns to its initial position as shown by Fig. 3.

Having described my invention, what I claim as new and desire to secure by Letters Patent of the United States is:

1. A machine for inserting fasteners having non-circular barrels, comprising a fastener-inserting tool, a raceway for supplying such fasteners to said tool, and mechanism for relatively moving said raceway and said tool to transfer a fastener to the latter and to turn the fastener relatively to said tool while the fastener is in contact with and under control of said raceway.

2. A machine for inserting fasteners having non-circular barrels, comprising fastener-inserting mechanism including an inserting tool, a raceway arranged to present such a fastener to said tool in a position other than the final position with regard to turning about the axis of the fastener barrel, and means for relatively moving said raceway and said tool as to turn the presented fastener about said axis to its final position before the fastener is disengaged from the raceway.

3. A machine for inserting fasteners having non-circular barrels, comprising a fastener-inserting tool, means arranged to present such a fastener to said tool, and mechanism for relatively moving said means and said tool to transfer the fastener to said tool and simultaneously to turn the fastener relatively to said tool to a predetermined position relatively thereto while the fastener is engaged with and under control of said presenting means.

4. A machine for inserting eyelets having non-circular barrels comprising a raceway, a non-rotary eyelet-inserting tool having a tapered spindle for taking an eyelet from said raceway, said spindle having a cross-section conforming substantially to the non-circular hole in the eyelet, and mechanism for relatively moving said raceway and said spindle to transfer the eyelet to said spindle and to turn the eyelet from a non-registering to a registering position while the eyelet is in contact with and under control of said raceway.

5. A machine for inserting eyelets having

- non-circular barrels, comprising a raceway, an eyelet-inserting tool having a spindle for taking an eyelet from said raceway, said spindle having a body portion conforming substantially to the non-circular hole in the eyelet and having an entering end the greatest diameter of which is less than the smallest diameter of said hole, mechanism for moving the delivery end of said raceway to and from register with said entering end of the spindle, and mechanism for moving said spindle into the eyelet at said delivery end, said raceway being formed and arranged to turn the eyelet about said end of the spindle to a predetermined position while said end of the spindle is moving through the eyelet. 10
6. A machine for inserting eyelets having non-circular barrels comprising a raceway, an eyelet-inserting tool having a spring-pressed spindle for taking such an eyelet from said raceway, said spindle having a tapered end portion and a body portion conforming substantially to the non-circular hole in the eyelet, mechanism for relatively moving said spindle and said raceway lengthwise of the spindle far enough to impale the leading eyelet on said end portion of the spindle, and mechanism for relatively moving the delivery end of the raceway and said spindle laterally 20 to turn said eyelet about said end portion of the spindle to a predetermined position and to disengage the impaled eyelet from the raceway after said eyelet has been turned as aforesaid. 25
- 35 7. A machine for inserting eyelets having non-circular barrels comprising a raceway, an eyelet-inserting tool having a spring-pressed spindle for taking such an eyelet from said raceway, said spindle having a tapered end portion and a body portion the cross-section of which conforms substantially to the non-circular hole in the eyelet, mechanism for moving said tool to insert said end portion through an eyelet in said raceway, and mechanism for moving the delivery end of said raceway to and from register with said tool, said two mechanisms being coordinated to cause said raceway to turn said eyelet about said end portion to a predetermined position and 40 to insert said body portion into the eyelet before the latter is disengaged from the raceway. 50
8. A machine for inserting eyelets having non-circular barrels comprising a raceway having a detent at its delivery end, an eyelet-inserting tool having a spindle for picking such an eyelet from said raceway, said spindle having a tapering end portion and a body portion of non-circular cross-section conforming substantially to the non-circular hole in the eyelet, mechanism for moving said tool to insert said end portion of the spindle into an eyelet at the supply side of said detent, and mechanism for moving said delivery end to 55 and from register with said end portion of the 60
- spindle, said two mechanisms being coordinated to turn the impaled eyelet about said end portion of the spindle to a predetermined position before said eyelet is freed from said detent and to insert said body portion of the 70 spindle into the eyelet before the latter is disengaged from said raceway. 75
9. A machine for inserting eyelets having non-circular barrels comprising a raceway having an abrupt turn at its delivery end to arrest the leading eyelet, an eyelet-inserting tool having a spindle to pick an eyelet from the raceway, said spindle having a tapered end and a body portion of a cross-section conforming to the non-circular hole in the eyelet, mechanism for moving said tool to insert said tapered end through an eyelet at said abrupt turn, and mechanism for retracting the delivery end of said raceway to detach the impaled eyelet therefrom, said two mechanisms being coordinated to turn the impaled eyelet from a non-registering to a registering position relatively to the cross-section of said body portion and to insert said body portion of the spindle into the eyelet before disengaging said eyelet from the raceway. 80 85
10. A machine for inserting fasteners having non-circular barrels comprising a fastener-inserting tool having a spindle adapted to enter the barrel of such a fastener, a raceway arranged to supply such fasteners to said spindle, mechanism for operating said tool, and mechanism for operating said raceway, said raceway being formed and operated to turn a fastener on said spindle to a predetermined position and said spindle being formed to maintain the fastener in said predetermined position. 90 95
11. A machine for inserting eyelets, the barrels of which have one or more flat sides, comprising a raceway for supplying such fasteners, a fastener-inserting tool having a tapered spindle adapted to pick such an eyelet from said raceway, mechanism for operating said raceway, and mechanism for operating said tool, said raceway being formed and operated to turn an eyelet on said spindle to place a flat side of the eyelet in a predetermined position, and said spindle having one or more flat sides corresponding to those of the eyelet to maintain the specified flat side of the eyelet barrel in said predetermined position. 100 105 110 115
12. A machine for inserting eyelets having flat-sided barrels, comprising a raceway having a corner at its delivery end, a fastener-inserting tool having a non-rotatable spindle for detaching an eyelet from said raceway, said spindle having a body portion shaped to conform to the hole in such an eyelet and having a relatively small end portion about which the eyelet may turn, mechanism for relatively moving said tool and the raceway to thrust said body portion of the spindle into the eyelet, and mechanism for relatively moving 120 125 130

said tool and said raceway transversely of said spindle, said two mechanisms being co-ordinated to effect a wiping action of said corner on the eyelet barrel while said end portion of the spindle is in the eyelet to turn the latter into register with said body portion of the spindle and thereafter to insert said body portion into the eyelet before disengaging the latter from the raceway.

10 13. A machine for inserting eyelets, the barrels of which have a major diameter and a minor diameter at right angles to each other, comprising an eyelet-inserting tool having a tapered spindle formed with a 15 cross-section having a major and a minor diameter, a raceway formed to deliver an eyelet to said spindle in non-registering position with regard to said diameters, and mechanisms for relatively moving said tool and 20 said raceway to transfer the leading eyelet in the raceway from the latter to said spindle, the delivery end of said raceway having a portion formed and arranged to act on the barrel of the eyelet to turn the latter so that 25 its major and minor diameters will register with those of the spindle before the eyelet is disengaged from the raceway.

14. An eyelet-inserting machine comprising means arranged to feed an article of 30 work step by step, an eyelet-inserting tool, a raceway for supplying eyelets having flat-sided barrels to said tool, said raceway being arranged to extend substantially at right angles to the line of work-feeding movement, 35 said tool and said raceway having cooperative surfaces arranged to engage a flat side of each eyelet barrel to turn said flat side into parallel relation to said lines of work-feeding

movement, and mechanisms for relatively moving said tool and said raceway to turn the leading eyelet in the latter as aforesaid and thereafter to detach said eyelet from the raceway.

15. A machine for inserting fasteners having barrels elongated in cross-section comprising a raceway arranged to maintain such fasteners with the major diameters of their barrels extending lengthwise of the raceway, a spindle operative to pick the fasteners one by one from the delivery end of the raceway, and means for rotating each fastener about the axis of its barrel as its barrel is entered by the spindle and before it is moved out of the raceway.

16. An eyelet-inserting tool comprising a 55 spindle having a body portion of elongated cross-section and an entering end of relatively small cross-section offset laterally from the longitudinal median line of said body portion.

17. A spindle for an eyelet-inserting tool, said spindle having a body portion of elongated cross-section, and a substantially circular entering end offset laterally from the longitudinal median line of said body portion.

18. A spindle for an eyelet-inserting tool, said spindle having a body portion of elongated cross-section, an entering end of relatively small cross-section offset laterally from the longitudinal median line of said body portion, and a tapering portion extending from said entering end to said body portion.

In testimony whereof I have signed my name to this specification.

SYLVESTER L. GOOKIN.
